UNITED STATES PATENT OFFICE.

IRA H. SPENCER, OF WEST HARTFORD, CONNECTICUT, ASSIGNOR TO THE SPENCER TURBINE COMPANY, OF WEST HARTFORD, CONNECTICUT, A CORPORATION OF CONNECTICUT.

CLEANING IMPLEMENT.

Application filed August 22, 1925. Serial No. 51,868.

My invention relates more especially to the class of pneumatic cleaning implements that are attached to the end of a handle and connected by a hose with a suitable 5 vacuum producing apparatus, and an object of my invention, among others, is the production of an extremely light and efficient tool embodying a brush as a means for removing dust and dirt in connection with a 10 current of air flowing inwardly through the tool; and a further object of my invention is to provide a tool of this class in which the means for operating the brush shall be extremely simple thereby enabling it to be incorporated in a tool of minimum size. 15

One form of cleaning tool embodying my invention and in the construction and use of which the objects herein set out, as well as others, may be attained, is illustrated in 20 the accompanying drawings, in which—

Figure 1 is a view in front elevation of a cleaning tool embodying my invention.

Figure 2 is a top view of the same.

Figure 3 is a view, scale enlarged, in 25 vertical central section of one end of the tool.

Figure 4 is an end view same scale as (Figures 1 and 2).

Figure 5 is a view similar to Figure 3, 30 but showing a little different construction.

Figure 6 is a detail view of the central portion of the tool looking at the back.

Figure 7 is a view in section on a plane denoted by the dotted line 7—7 of Figure 6.

Figure 8 is a view similar to Figure 7, but 35 showing the cap for the gear housing secured in place.

In the accompanying drawings the numeral 10 indicates the nozzle or case embodied in my improved cleaning tool or implement, which case is of a size to enable it to be readily attached to a handle commonly employed in pneumatic cleaning operations, this case preferably being of circular shape 40 in cross section, closed at its ends, and having a mouth 11 at the bottom thereof. Hubs 12 are formed on the ends for the reception of rollers or wheels 13.

In the use of the tool it is desirable that 45 the mouth 11, as well as a brush, to be here-

inafter described, located therein, may be adjusted relatively to the surface being cleaned, and for this purpose I place an eccentric bearing 14 for the wheel 13 upon the hub 12, this eccentric bearing having a disc 55 15 by means of which it may be rotated and a nut 16 being employed to secure it in place when it has been adjusted to suit any special requirements.

A tubular neck or extension 17 projects 60 from the back of the casing, this extension being of a shape to be readily received within the end of a tubular cleaning tool handle hereinbefore referred to, which handle will be readily understood by those skilled in the art and a showing therefore being omitted 65 herein.

A supporting web 18 projects inwardly from the back of the case at about its lengthwise center and a gear housing 19 is formed 70 preferably integral with said web, said housing having a cover 20 as a means of closing one end thereof. A worm gear 21 is rotatably mounted within the housing as by means of hollow hubs 22 located in bearing 75 openings in the housing 19 and the cover therefor, and as shown in Figure 3 of the drawings. The gear 21 meshes with a worm 23 secured to a worm shaft 24 mounted in a bearing tube 25 projecting from the housing 19 and preferably integrally formed 80 with the web 18. The shaft 24 is suitably mounted in bearings 26 in the tube 25, and as shown in Figure 7 of the drawings. A win wheel or propeller 27 is secured to the shaft 24 at the end of the tube 25 and in an air passage 28 in the tubular extension 17 through which passage the air used for 85 cleaning purposes passes from the mouth 11 to the handle and the hose and to the apparatus employed for producing a vacuum to create such flow of air. It will thus be seen that the propeller is driven by the air that is employed for regular cleaning purposes.

A hole extends through the hubs 22, this 90 hole being preferably of angular shape in cross section to receive the angularly shaped ends 29 of brush shafts 30, the opposite ends of each shaft being mounted in a bushing 95 100

31 in a hole in one of the hubs 12. There are two of these shafts 30 projecting in opposite directions from the housing 19 and each of the shafts bears a brush including a 5 core 32 of wood or other suitable material to which bristles or other brush material 33 is secured in any suitable manner. A spring 34 may be employed within the hole in the hubs, said spring being located between the 10 ends of the shafts 30 and operating to thrust them apart. This construction permits the brushes to be moved endwise within the hubs for removal of said brushes when desired. In the structure shown in Figure 5 this 15 spring is omitted, the construction being otherwise the same as hereinabove set forth.

A pocket 35 is formed preferably as a part of the case 10, this pocket being located on top of the case and having a communicating 20 opening 36 with a chamber 37 in the case and in which the cleaning brush is located. The opening 36 is preferably arranged tangentially to the rotating brush, so that 25 heavier particles of matter may be thrown off by the centrifugal action of the brush through the opening 36 and into the pocket 35, being guided by the curved wall 38 within the pocket. A guard 39 projects upwardly within the pocket to retain accumulated 30 matter therein and prevent it from falling out through the opening 36.

In accordance with the provisions of the patent statutes I have described the principles of operation of my invention, together 35 with the device which I now consider to represent the best embodiment thereof, but I desire to have it understood that the device shown is only illustrative and that the invention may be carried out by other 40 means and applied to uses other than those above set out.

I claim—

1. A cleaning implement comprising a case having an inlet mouth and an outlet 45 passage, a brush rotatable within the case, means within the case for rotating said brush, hubs projecting from the ends of the case, means within the hubs for supporting the brush, eccentric bearing sleeves enclosing 50 said hubs and rotatably adjustable thereon, independently of said brush, and supporting wheels rotatably mounted on said eccentric bearing sleeves.

2. A cleaning implement comprising a 55 case having an inlet mouth and an outlet passage, a brush rotatably mounted within the case, means within the case for rotating said brush, a hub projecting from the end of the case, an eccentric rotatably mounted on said hub, an adjusting disc projecting from the eccentric and spaced from the side of the case, a supporting wheel for said case, said wheel being mounted on said eccentric, between said case and said disc

and means for locking the eccentric in different positions of adjustment.

3. A cleaning implement comprising a case having an inlet mouth and an outlet passage, a hub projecting from the end of the case, a bushing located within said hub, a brush comprising a shaft with its end rotatably mounted in said bushing, means within the case for rotating said brush, an eccentric mounted on said hub, a supporting wheel rotatably mounted on said eccentric, and means for locking the eccentric in different positions of adjustment.

4. A cleaning implement comprising a case having an inlet mouth and an outlet 80 passage, means for supporting said case, a driving member rotatably supported within the case and having coaxial openings therein, means for rotating said driving member, and brushes located on opposite sides of said driving member with their outer ends journaled in the case and their adjacent inner ends spaced from each other and slidably mounted within said openings of said driving member for rotation thereby, 85 but for longitudinal movement toward each other independently of said driving member, whereby the opposite outer ends of said brushes may be removed from their bearings to permit removal of the brushes from the 90 case.

5. A cleaning implement comprising a case having an inlet mouth and a tubular neck for connection with a tube for the passage of air, a brush rotatably mounted in the case, means for rotating said brush, a pocket located on top of said case, and a guard projecting into said pocket, said pocket having a directing wall curved to direct material thrown off from said brush into said 100 pocket behind said guard, said case having an opening above said neck and said brush to permit passage of said material thrown off from the brush into said pocket.

6. In a vacuum cleaner, the combination 110 with a suction tube having a transverse nozzle, of a transverse cylindrical brush mounted in said nozzle, means actuated by the passage of air through said tube for imparting rotation to said cylindrical brush, a pocket formed on top of the nozzle and having a communicating opening with the chamber of the nozzle above the suction tube, and a guard projecting upwardly within the pocket to retain matter thrown upwardly into the pocket by the brush.

7. In a vacuum cleaner, a transverse nozzle having a central rearwardly projecting tubular neck adapted for connection by means of a tubular handle with a suction apparatus, said nozzle having a bottom mouth, a transverse cylindrical brush mounted in the nozzle to project through its mouth, a longitudinally arranged shaft having its forward end geared to the brush 125 130

and projecting rearwardly into said neck, and a propeller on the rear end of said shaft adapted to be rotated by the passage of air through said neck for actuating said cylindrical brush.

8. A cleaning implement comprising a case having an inlet mouth and a tubular neck for connection with a suction tube, a brush rotatably mounted in the case, and 10 means for rotating said brush, said case having a pocket positioned above the brush and the entrance to said neck so as to receive heavy particles of material thrown from the brush by centrifugal force.

15 9. A cleaning implement comprising a case having an inlet mouth with an elongated opening and a laterally extending outlet passage from substantially the lengthwise center of the case, a thin web extending 20 transversely within the case and formed integral with one wall substantially in the lengthwise center thereof, a housing supported by the edge of said web and a bearing supported on the edge of said web and 25 projecting rearwardly through the inlet passage, a driving shaft projecting through said bearing into said housing, a propeller secured to the end of the shaft in said outlet passage, brushes mounted within said case 30 on opposite sides of said housing, and having shafts with adjacent ends projecting into said housing, and a driving connection between said driving shaft and the shafts of said brushes.
